United States Patent Office.

ROBERT H. JEFFORD, OF NEW YORK, N. Y., ASSIGNOR TO ABRAHAM G. JENNINGS, OF SAME PLACE.

Design No. 4,337, dated September 6, 1870.

DESIGN FOR NET FABRIC.

The Schedule referred to in these Letters Patent and making part of the same

all whom it may concern:

Be it known that I, ROBERT H. JEFFORD, of the city, county, and State of New York, have invented a new and original Design for Net Fabric; and I do hereby declare that the following is a full, clear, and exact description thereof, which will enable others skilled in the art to make and use the same, reference being had to the accompanying drawing forming part of this specification, in which the drawing represents a face view of my new design.

This invention relates to a new design for an open mesh or net fabric, and consists in the arrangement of alternate hexagonal and diamond-shaped rows of meshes or openings.

The rows *a a* of diamond-shaped openings are

formed by diagonal threads or pillars, as shown. By connecting the corners of opposite rows of diamonds with straight threads or pillars *b*, the hexagonal rows *c c* of meshes are formed, as shown.

Between every two rows of hexagonal meshes there may be but one row of diamonds, as at 1, or two, as at 2, in the drawing.

I claim as my invention—

The design for net fabric, as shown.

The above specification of my invention signed by me this 1st day of August, 1870.

ROBERT H. JEFFORD.
